UNITED STATES PATENT OFFICE.

OWEN J. CONLEY, OF NEW YORK, N. Y.

CONVEYER FOR UNLOADING VESSELS.

SPECIFICATION forming part of Letters Patent No. 625,085, dated May 16, 1899.

Application filed May 10, 1898. Serial No. 680,242. (No model.)

To all whom it may concern:

Be it known that I, OWEN J. CONLEY, a citizen of the United States, residing at New York, in the county of New York and State 5 of New York, have made a new and useful Invention in Conveyers for Unloading Vessels, of which the following is a specification.

My invention has for its objects, first, to so construct a vessel that the material carried thereby—such, for instance, as coal, crushed ore, sand, grain, or the like—may be removed therefrom by a conveyer located beneath the entire load and elevated to a point above the deck of the vessel and then convey it to any 15 point of delivery within range of a universally-adjustable conveyer carried by the vessel, and, second, to adapt such a vessel and its conveying and elevating apparatus to the purpose of unloading such materials on board 20 of a vessel at sea.

My invention will be fully understood by referring to the accompanying drawings, in which—

Figure 1 is a longitudinal sectional view of a vessel constructed in accordance with my invention and illustrating in part sectional 25 part elevational view my novel apparatus for removing and elevating a load of material carried thereby. Fig. 2 is a transverse sectional view thereof, taken on the broken line $x x$, Fig. 1, and as seen looking at that figure from the left toward the right-hand side of the drawings in the direction of the arrows. Fig. 3 is an enlarged plan view of the mechanism for controlling the movement of the exterior conveyer or elevator and for permitting the upper or free end thereof to be moved at will in all directions; and Fig. 4 is a side elevational view of the same mechanism, a sectional view being taken through the body of the apparatus in order to illustrate more clearly the king bolt or pin which permits the apparatus to partake of lateral movement.

Referring now to the drawings in detail, in 45 which like letters of reference represent like parts wherever used, H represents the hull of a vessel, and $K K$ the decks of the carrying or conveying part thereof, the same being inwardly inclined, preferably at an angle of 50 about forty-five degrees, and trussed or otherwise supported in such manner as to sustain the load thereon.

H' H^2 H^3 to H^7 , inclusive, represent discharging-hoppers located at the bottom of the V-shaped deck, and $d d d$ are sliding doors 55 adapted to close the lower ends of said discharging-hoppers, the entire arrangement being such that when coal, crushed ore, or analogous material is placed upon said decks the tendency thereof will be to move downward 60 into the hoppers H' H^2 H^3 , &c.

R R' R^2 to R^6 , inclusive, are rollers journaled in standards $t t$ secured to the bottom of the vessel, R' to R^6 , inclusive, being located directly beneath the discharging-hoppers H' to H^7 , inclusive. O is a conveyer-belt of well-known form carried by said rollers and adapted to receive the material from the discharging-hoppers H' to H^7 , inclusive. On the shaft which supports the driving-roller 70 R are two pulleys P and P' , (see Fig. 2,) one of said pulleys being in alinement with the corresponding pulley upon the fly-wheel shaft of a donkey-engine E , located in an independent compartment near the bow of the vessel 75 and connected thereto by a belt b , the arrangement being such that the engine will drive the conveyer-belt O in the proper direction to advance the material from left to right.

O' is an elevator-belt carried by rollers E' 80 E' , properly supported, respectively, near the bottom of the vessel and above the deck thereof and provided with the usual elevator-buckets, as shown, and O^2 is a conveyer or elevator belt carried by a trussed frame T , 85 pivotally supported at the opposite ends of the roller E^2 , which in turn is supported by a king bolt or pin C in a metallic standard F , resting upon a truss or frame G on the upper deck of the vessel. The outer end of the truss 90 T is adjustably sustained by a block and fall consisting of pulleys $p p$ and a rope r , the upper pulley p being pivotally secured by a link to the upper end of a derrick D , secured to the upper deck near the bow of the vessel. 95

W is a winch to which is secured the free end of the rope r , and $g g g g$ are guy-ropes secured, respectively, to the upper end of the derrick and the sides of the vessel.

$g' g^2$ are guy-ropes secured at the outer end 100 of the truss T .

Referring now to Figs. 3 and 4, $P^2 P^3$ are pulleys carried by a shaft journaled in standards $S S'$ of the metallic framework D' , and

- B B' B² B³ are beveled gear-wheels, the gear-wheel B meshing with the lower gear B' and the upper gear B² with the gear B³, carried by the same shaft which supports the driving 5 roller or drum E² for the outer and upper conveyer or elevator belt O². The lower gear-wheel B' is seated in the upper surface of an extension F of the metallic framework D', and it, together with the standards J J, which 10 pivotally support the lower end of the truss T, is secured thereto by a king bolt or pin C, so that the outer conveyer or elevator may partake of lateral motion in either of two directions and vertical motion about its pivotal 15 supports upon the standards J J.
- The pulley P', Fig. 2, is connected by a belt b' with the pulley P², and the pulley P³, upon the same shaft as the pulley P², is in turn connected by a belt b² with a pulley P⁴ 20 upon a shaft journaled in the framework of the derrick D, which pulley is in turn connected by a belt b³ with a pulley carried by the same shaft which supports the driving-roller E' of the elevator-belt O'.
- E⁴ is a hopper located in front of and below the upper end of the elevator-belt O' and adapted to convey the material therefrom to the lower end of the outer conveyer or elevator belt O². 25
- The outer or free end of the truss T is provided on its opposite sides with guy-ropes g' g² for the purpose of securing it in any desired position and also for facilitating its movements laterally about the pivotal point 30 of support in the nature of the king bolt or pin C, said guy-ropes also, when secured on shore, being adapted to prevent any movement of this part of the conveyer owing to the action of the mechanism itself. These guy-ropes are 35 also designed to be used as a means of securing the vessel to the side of a steamer or other vessel while coaling at sea.
- The operation of the entire apparatus is as follows: The load to be carried by the vessel 40 is placed in the carrying-compartment, consisting of the inclined decks K K, the sliding doors d d d of the discharging-hoppers H' to H⁷ having all first been closed. The vessel is secured to the dock, and the outer or free 45 end of the truss T, which carries the outer conveyer or elevator belt O², is secured by the guy-ropes referred to and the proper elevation given thereto by the block-and-fall mechanism and winch W. The donkey-engine 50 is now set in motion in the proper direction to cause the upper portion of the conveyer-belt O to move from left to right or from the stern toward the bow of the vessel and at the same time to give, through the 55 agency of the several belts b' b² b³ and pulleys P' P² P³ P⁴, the proper movement to cause the buckets of the elevator-belt O' to advance the material upward. At the same time the 60 gear-wheel B imparts motion through the gear-wheels B', B², and B³ to the driving-roller E' in the proper direction to give to the conveyer or elevator belt O² forward motion.

The sliding door d of the first discharging-hopper H' is now withdrawn and the material allowed to descend by its own weight 70 upon the surface of the conveyer-belt O, and as it descends it is carried forward and upward and ultimately discharged at the upper end of the conveyer or elevator belt O². In like manner the succeeding doors d are withdrawn, and the entire load is thus completely discharged through the sole agency of the conveyer itself. 75

It is apparent that coal, powdered or crushed ore, or analogous material might be carried in 80 the lower compartment beneath the decks and shoveled or otherwise transferred to the upper surface of the conveyer-belt O, thus giving to my novel form of vessel the capacity of carrying an additional load below the inclined decks. 85

Although I have hereinbefore described my invention as applicable for unloading a vessel at a dock, it is apparent that the same may have other uses—as, for instance, it has 90 especial use in the delivery of coal to vessels either at sea or at a dock, its adjustability rendering it a very desirable means of effecting this result. It is also to be understood that my invention is applicable for use with 95 all kinds of material capable of descending through the discharging-hoppers H' to H⁷, inclusive—such, for instance, as salt, sugar, iron, ore, coal, crushed rock, or analogous materials. 100

I am aware that it is not broadly new with me to devise a vessel having inclined sides and discharge-hoppers adapted to discharge the material carried thereby upon a conveyer located beneath said hoppers and convey it 105 to an elevator located near one end of the vessel, which in turn conveys it to a point of discharge on shore or elsewhere, and I make no claim hereinafter broad enough to include such a structure. 110

Having thus described my invention, what I claim, and desire to secure by Letters Patent of the United States, is—

1. The combination of a vessel, a conveyer located in a compartment beneath the entire 115 load carried by the vessel, an elevator adapted to receive the material discharged from said conveyer and elevate the same; a second conveyer adapted to receive said material from the upper or delivery end of the elevator, said second conveyer being pivotally secured to the deck of the vessel in such manner as to adapt its free or delivery end to be moved in any desired direction, together with means carried also by the vessel for elevating 120 the free or delivery end of said second conveyer to a point above the delivery end of the elevator, whereby the material carried by the vessel may be elevated and unloaded at various heights and angles, substantially as shown 125 and described.

2. The combination of a vessel, a conveyer located in a compartment beneath the entire 130 load carried by the vessel, an elevator adapt-

ed to receive the material discharged from said conveyer and elevate the same; a second conveyer adapted to receive said material from the upper or delivery end of the elevator, said second conveyer being pivotally secured to the deck of the vessel in such manner as to adapt its free or delivery end to be moved in any desired direction and raised to a point above the delivery end of the elevator; a derrick secured also to the deck of the vessel, together with block-and-fall mech-

anism pivotally connecting the second conveyer with the top of the derrick and means, as a winch, for elevating the free or delivery end of said second conveyer to any desired height, substantially as described.

In testimony whereof I have hereunto subscribed my name this 7th day of May, 1898.

OWEN J. CONLEY.
